UNITED STATES PATENT OFFICE.

RIENHART WILKEN, OF STERLING, ILLINOIS.

SNOW-PLOW.

No. 830,871.

Specification of Letters Patent.

Patented Sept. 11, 1906.

Application filed December 29, 1905. Serial No. 298,717.

To all whom it may concern:

Be it known that I, RIENHART WILKEN, a citizen of the United States, residing at Sterling, in the county of Whiteside and State of Illinois, have invented certain new and useful Improvements in Snow-Plows; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention has reference to snow-plows, and pertains more particularly to that class of such devices which are intended for use in cleaning sidewalks and paths. There is chiefly comprised therein a blade pivotally supported at the forward end of a frame mounted on carrying-wheels and provided with handles by which the machine is operated or guided. Mechanism is provided for adjusting the height of the blade and also for adjusting the position of such blade with reference to the line of travel of the machine.

The device possesses other novel features, which will be more particularly pointed out in the specification, reference being had to the accompanying drawings, in which—

Figure 1 is a plan view of my device. Fig. 2 is a vertical longitudinal section in the line $x-x$ of Fig. 1. Fig. 3 is an enlarged detail showing the forward end of one of the shoes 17.

Fig. 4 shows a modified form of certain parts of my invention whereby it is adapted to be used with animal power.

Similar numbers refer to similar parts throughout the several figures.

1 represents the frame of the machine, the front part of which is supported on a wheel 2, fixed on an axle 3, journaled at its ends in such frame. The rear part of the frame 1 is supported by a pair of wheels 4, fixed on an axle 5, also journaled at its ends in said frame. Pivotedly secured in the front of the frame 1, as at a , is a standard 6, provided at its lower end with a forwardly-extending foot 7 and near its upper end with a perforated lug 8, to which foot and lug is pivotally attached at its vertical center the blade 9 of the plow. This blade may be made in any suitable form, but is preferably curved, as shown in the drawings.

Supported transversely of the frame 1 is an arch 10, and a pair of handles 11 is secured to

the sides of such arch and to the front end of the frame. The rear ends of the handles 11 are united by a rod 12 and cross-piece 13, said cross-piece being perforated to permit 60 the fastening thereto at their rear ends of a pair of braces 14, hingeably secured at their forward ends to the rear of the blade 9, near the ends thereof. The rear ends of the braces 14 are provided with series of perforations 15, 65 each of such braces being secured to the cross-piece 13 by means of a bolt 16 passing through one of the perforations 15.

Hingeably attached to the arch 10 is a pair of shoes 17, the forward ends of which are adjustably secured to the frame 1 by means of bolts 18 passing through slots 19 in the forward ends of such shoes and perforations in the frame 1. Fixed to the arch 10, centrally thereof, is a brace 20, the forward end of 75 which is secured to the standard 6 by means of a bolt 21 passing through a slot 22 in the brace 20 and a perforation in said standard.

In Fig. 4 is shown a modified form of my device, wherein a pair of braces 23 (one only shown) are attached at their rear ends to the frame 1 and curved upwardly and inwardly toward each other and attached to the upper end of the standard 6 by means of a bolt 24 passing through slots 25 in such braces and 85 a perforation in the standard 6. The braces 23 are projected forwardly into an extension 26, to which a horse or other animal may be secured in any known manner. In this construction the brace 20 is dispensed with. 90

In operation as a hand device the machine is forced ahead of the operator, the wheels 4 and 2 preventing the tendency of the blade to move laterally in a direction opposite to that to which the snow is thrown. If, on account of the slippery condition of the ground, there is still a tendency to side draft, the wheels may be reinforced by the shoes 17, which are lowered until they are on a line with the lower part of the wheel 2, as shown 100 in Fig. 2. To bring more weight upon such shoes, they can be adjusted until the wheel 2 is raised entirely from contact with the ground and the weight of the blade and forward part of the frame rests upon the shoes 105 alone. When it is not deemed necessary to use such shoes, they can be raised until the wheel 2 alone has contact with the walk and secured in such position until it is again desired to use them. To raise or lower the 110 blade 9, the bolt 21 is loosened and the upper end of the standard 6 moved in a forwardly

or rearwardly direction. If moved toward the rear, the front end of the foot 7 is thereby raised and with it the blade 9. If moved toward the front, the foot and blade are correspondingly lowered. By adjustment of the braces 14 the position of the blade 9 and direction of movement of the snow handled thereby may be reversed, or such blade can be set at any desired angle—from a right angle to the line of travel of the machine to the oblique position shown in the drawings. It will be seen that this can be readily accomplished by the operator from his position at the rear of the machine.

15 In the construction shown in Fig. 4, which is for machines of a larger size, the vertical adjustment of the blade is substantially the same as in the smaller machines, the bolt 24 being loosened and the upper end of the 20 standard 6 moved longitudinally in the desired direction, as before described. Upon a perfectly smooth walk, such as are constructed from cement, the blade can be set so as to be practically in contact with the walk at all 25 times. It is designed to have the blade 9 of such length as to result in the cleaning of the greater part of the walk, the snow being thrown entirely from the walk at one side thereof. When it is desired to change the 30 direction of delivery of the snow for any reason, it can be accomplished by adjustment of the blade 9, as above described.

If desired, the peripheries of the carrying-wheels can be corrugated and the shoes 17 35 can be constructed in any form which will be suited to the purpose for which they are intended.

What I claim as my invention, and desire to secure by Letters Patent of the United 40 States, is—

1. A machine of the class named, comprising a frame, mounted on carrying-wheels and provided with suitable guiding means; a blade, centrally hinged at the front of such 45 frame; means for adjustably holding such blade at a desired angle with reference to the line of travel of the machine; and means for increasing the amount of resistance of the machine to the side draft of the blade; substantially as set forth.

2. A machine of the class named, comprising a frame, mounted on carrying-wheels, and provided with suitable guiding means; a blade, centrally hinged at the front of such 55 frame; means for holding such blade adjust-

ably with reference to the line of travel of the machine; means for vertically adjusting the position of said blade; and means for increasing the amount of resistance of the machine to the side draft of said blade, substantially as and for the purpose named.

3. In a device of the class named, the combination with the frame of the machine, and carrying-wheels therefor, of the pair of handles 11, provided with the cross-piece 13; the blade 9, centrally hinged to the front of the frame; and a pair of braces 14, hingeably attached to the blade 9 near the ends thereof, and adapted to be adjustably secured to the cross-piece 13 at their rear ends, substantially as shown and described.

4. In a snow-plow, the combination of the frame 1, having suitable carrying means; the handles 11, provided with the cross-piece 13; standard 6, pivotally supported to the front of the frame; the blade 9, provided with braces 14, adapted to be adjustably secured at their rear ends to the cross-piece 13; and means for adjustably holding the upper end of the standard 6, substantially as set forth.

5. In a snow-plow, the combination of the frame 1, mounted on the wheels 2 and 4, and provided with the arch 10; the standard 6, pivotally supported to the front of the frame 1; the blade 9, centrally hinged to the standard 6; means for adjustably holding the blade 9 at a desired angle with reference to the line of travel of the machine; means for adjusting the position of the standard 6, to raise or lower the blade 9; and means for propelling 90 said machine, substantially as and for the purpose named.

6. In a machine of the class named, the combination of the frame 1, provided with rear carrying-wheels 4 and a front carrying-wheel 2; a pair of shoes 17, suitably supported on the frame 1, adjacent to the wheel 2, and on opposite sides thereof; the blade 9, centrally hinged to the front of the frame 1; means for adjustably holding the blade 1; means for vertically adjusting the shoes 17; and means for propelling said machine, substantially as shown and set forth.

In testimony whereof I affix my signature in presence of two witnesses.

RIENHART WILKEN.
